UNITED STATES PATENT OFFICE.

DAVID L. SHAFFER, OF PITTSBURG, PENNSYLVANIA.

STEAM-BOILER FURNACE.

SPECIFICATION forming part of Letters Patent No. 770,122, dated September 13, 1904.

Application filed April 21, 1903. Serial No. 153,676. (No model.)

To all whom it may concern:

Be it known that I, DAVID L. SHAFFER, a resident of Pittsburgh, in the county of Allegheny and State of Pennsylvania, have invented a new and useful Improvement in Steam-Boiler Furnaces; and I do hereby declare the following to be a full, clear, and exact description thereof.

My invention relates to steam-boiler furnaces; and its object is to improve the efficiency of such furnaces, and more especially to increase the heating-surface thereof.

A further object of the invention is to improve the grate construction of steam-boiler furnaces and provide novel means for shaking and cleaning the furnace.

The invention also comprises certain details of construction hereinafter described and claimed.

In the accompanying drawings, Figure 1 is a vertical longitudinal section through a locomotive fire-box constructed according to my invention. Fig. 2 is a transverse vertical section thereof on the line 2 2, Fig. 1, showing a modified form of shaker-frame and having parts omitted to avoid confusion. Fig. 3 is a section on the line 3 3, Fig. 1. Fig. 4 is a plan view of the drop-grate and rocking bar. Fig. 5 is a section on the line 5 5, Fig. 4. Fig. 6 is a plan view, and Fig. 7 a transverse section, of a modified form of drop grate-section and rocking bar. Fig. 8 is a plan view, and Fig. 9 a transverse section, of another modified form of drop grate-section and rocking bar. Fig. 10 is a bottom view of the modified form of shaker-frame. Fig. 11 is a top plan view of the preferred form of shaker-frame. Fig. 12 is a section on the line 12 12, Fig. 11; and Fig. 13 is a vertical section through one of the shaker-prongs and tube to which the same is connected.

In carrying out my invention the primary object to be gained is an increase in the heating area of the furnace. As a result the major portion of the furnace or fire-box is enclosed by a water-jacket, and this water-jacket also extends underneath the bottom of the furnace-chamber, thus forming a grate.

In the accompanying drawings my invention has been shown applied to a locomotive-

boiler; but it will be understood that it is equally as well adapted to any other form of fire-flue boiler, whether stationary, horizontal, upright, or of any other type of fire-flue boiler. In the drawings the furnace-chamber or fire-box is shown at 1, this being provided with the usual side sheets 2, crown-sheet 3, front or flue sheet 4, and rear sheet 5, as is the usual practice in locomotive-boilers. Surrounding this fire-box is the usual water-jacket 6, which communicates with the steam-generating space of the boiler, the sheets above mentioned forming the inner walls of said water-jacket and suitable sheets or plates 7 and 8 forming the outer walls of said water-jacket.

The usual practice is to connect the inner and outer walls of this water-jacket by means of stay-bolts; but in my improved furnace this connection is made by stay-tubes 10, which have their inner ends open and communicating with the furnace-chamber, while their outer ends are closed, as by welding plugs therein. These stay-tubes will be so connected to the inside and outside walls of the water-jacket as to form perfectly-tight joints.

Interposed between the walls of the water-jacket at their lower edges is the usual mud-ring 20, which is united to the walls by means of rivets 21 passing through said walls and ring. These rivets, however, are peculiar in that the inner face of the heads instead of being flat, as is usually the case, are formed tapering or conical, as indicated at 22, and the holes in the sheets will be provided with similar tapering or conical walls, so that when the rivets are upset the walls will be drawn tightly against the mud-ring and form a perfectly-tight joint.

In my device the water-jacket forms not only the side and end walls of the furnace-chamber, but also forms a major portion of the bottom or floor thereof. The remainder of the floor or bottom is formed by a tipping or drop grate-section, so as to facilitate the cleaning of the fire-box. The water-jacket underneath the furnace is shown at 24, and it is connected with the water-space of the boiler, as usual. The top and bottom walls of this water-jacket are connected by stay-

tubes 25, which are connected to the walls in any suitable way so as to form a tight joint. At the edge of the opening where the drop grate-section is placed the floor-walls are separated by the mud-ring 20 and united by rivets 21. The water-jacket of the boiler will be provided with suitable cleaning-holes which are closed by plugs 26.

I provide suitable fingers or prongs 29, projecting up through the stay-tubes 25 and which are given an up-and-down movement to shake down the ashes and break up the fire. To accomplish this movement, said prongs are connected in any suitable way to a skeleton frame 30, formed in any suitable way, such as by longitudinal and cross members, which may be solid bars, as shown in Figs. 2 and 10, but which preferably are tubular, as shown in Figs. 1, 11, 12, and 13. The shaker-frame 30 is engaged by rock-arms 31, pivoted in suitable hangers 32 and having arms 33, which are connected, by means of a link or connecting rod 34, to a suitable operating means, such as the lever 35. By moving this lever back and forth the shaker-frame 30 will be raised and lowered, thus causing the prongs to reciprocate up and down and shake down the ashes and break up the fire. To reduce friction, the ends of the arms 31 are provided with rollers 36, which bear against the shaker-frame. Short sections of chain 37 connect the arms 31 with the shaker-frame, so that if there should be any tendency of the shaker-frame to stick when in the elevated position these chains will pull it down when the rock-arms move downwardly.

In some cases it may be desirable to introduce a blast, such as air or steam, to the fire, and when this is desirable such blast can be conveniently introduced by making the shaker-frame 30 and prongs 29 hollow or tubular, as shown in Figs. 1 and 11 to 13. The shaker-frame will be provided with a suitable hose connection 38, whereby it can be connected either to the air-reservoir or to the steam-space of the boiler in order to supply a blast of air or steam to the fire. This will do away with the necessity for the strong exhaust which is usually introduced in the stack and will prevent the smoke-box becoming clogged or filled with cinders or charred coal.

The drop grate-section, which preferably will be employed in all large furnaces, can be made of various forms. In Figs. 4 and 5 it is shown as a frame or casting 39, hinged at 40 and having a downwardly-projecting arm 41, to which is connected an operating-rod 42. This grate-section comprises longitudinal side bars 43 and a series of cross connecting-bars 44. Pivotedly mounted in this section is a rocking bar which comprises a series of transverse fingers 45, secured to the rock-shaft 46. The latter has a downwardly-projecting arm, to which is connected a rod 48, having its rear end connected to operating means, such as a

lever. The shaft 46 is so mounted in the drop-section as to be below the top surface thereof, thus protecting said shaft from the heat and also permitting the fingers 45 to sweep the full length of the slots in the drop-section. 70

In Figs. 6 and 7 the cross-bars of the grate-section are broken at their middle, so as to present two series of teeth 50, projecting inwardly from the side bars. This construction permits the rocking bar to be inserted from the top of the grate-bar instead of from the bottom. In order to strengthen this form of grate-section, a wrought iron or steel rod or band 51 is placed in a groove entirely surrounding the grate-section. In Figs. 8 and 9 the grate-section comprises a stationary section 53 and a pivoted or tilting section 54, the rocking bar being pivotally mounted in the stationary section 53. Various other forms 80 of grate-sections may be employed. 75

Both the connecting-rod 42 for the tilting grate-section and the connecting-rod 48 for the rocking bar may be connected to the same operating means, such as to the lever 56, (shown in Fig. 1,) one of said connecting-rods being secured above the fulcrum of the lever and the other below the same, so that by operating the lever the grate-section and rocking bar will both be oscillated and in opposite 95 directions.

My invention may be modified in details of construction without departing from the spirit thereof and, as above stated, it is applicable to any form of steam-boiler and is not to be 100 limited to a locomotive-boiler such as shown.

With my improved furnace a very large increase in the heating-surface is obtained, so that the efficiency of the furnace is very greatly increased. Furthermore, the arrangement presents a convenient means for the introduction of air or steam blast to the fire, this being accomplished by the hollow shaker-frame and fingers. (Shown in Figs. 1 110 and 11 to 13.)

What I claim as my invention, and desire to secure by Letters Patent, is—

1. A steam-boiler furnace comprising a fire box or chamber, a water-jacket forming the floor or grate for a portion of said chamber, a drop-section forming the grate for another portion of said chamber, said water-jacket having passages extending therethrough, fingers or prongs projecting through said passages, and means for raising and lowering said fingers. 115

2. A steam-boiler furnace comprising a fire box or chamber, a drop-section forming the grate or floor for a portion of said chamber, water-jacket walls forming the floor for the 120 remaining portion of said chamber, stay-tubes connecting said walls, fingers or prongs projecting through said tubes, and means for raising and lowering said fingers. 125

3. A steam-boiler furnace comprising a fire 130

- box or chamber, a drop-section forming the floor or grate for a portion of said chamber, a water-jacket forming the floor or grate for the remainder of said chamber, provided with 5 passages therethrough, a frame provided with fingers or prongs projecting through said passages, rocking arms bearing against said frame, and means for rocking said arms to raise and lower said frame.
- 10 4. A steam-boiler furnace comprising a fire box or chamber, a water-jacket forming the floor or grate thereof, stay-tubes connecting the walls of said water-jacket, a shaker-frame provided with fingers or prongs projecting 45 through said stay-tubes, rock-arms pivotally mounted below said frame and bearing against the same, chains or the like connecting said arms and frame, and means for rocking said arms.
- 15 5. A steam-boiler furnace comprising a fire box or chamber, a water-jacket forming the floor or grate thereof provided with passages therethrough, hollow prongs projecting through said openings, and steam or air connections to said prongs. 50
- 20 6. A steam-boiler furnace comprising a fire box or chamber, a water-jacket forming the floor or grate thereof, stay-tubes through said water-jacket, a shaker-frame provided with 55 fingers or prongs projecting through said tubes, means for raising and lowering said shaker-frame, said shaker-frame and fingers being hollow and said fingers being provided with openings, and air or steam connections 60 to said shaker-frame.
- 25 7. A steam-boiler furnace comprising a fire 65
- box or chamber, a water-jacket forming the floor or grate thereof and provided with an opening therethrough, a metal piece interposed between the top and bottom sheets of 40 the water-jacket around said opening, rivets passing through said sheets and interposed metal piece, and a drop grate-section located in the opening in said water-jacket.
8. A steam-boiler furnace comprising a fire 45 box or chamber, a water-jacket forming the floor or grate for a portion of said chamber, a drop grate-section for the remainder of said chamber, and a rocking bar mounted in said drop grate-section. 50
9. A steam-boiler furnace comprising a fire box or chamber, a grate-section therefor pivotally mounted at one of its edges, a rocking bar pivotally mounted in said grate-section with the pivots below the top surface of said 55 section, and means for oscillating both said grate-section and rocking bar.
10. A steam-boiler furnace comprising a fire box or chamber, a grate-section therefor pivotally mounted at one of its edges, a rocking 60 bar pivotally mounted in said grate-section with the pivots below the top surface of said section, an oscillating lever, and links connecting the opposite ends of said lever with said rocking bar and grate-section. 65

In testimony whereof I, the said DAVID L. SHAFFER, have hereunto set my hand.

DAVID L. SHAFFER.
